DEEP WELL COOKER

Edwin A. Rutenber, Greenville, Mich., assignor to
 Gibson Refrigerator Company, Greenville,
 Mich., a corporation of Michigan

Application July 31, 1948, Serial No. 41,865

7 Claims. (Cl. 219—37)

1

This invention relates to a deep well cooker and method of producing same. The invention is particularly useful in connection with a deep well cooker in which the heating element may be supported in the lower portion of the well and alternatively in the upper portion of the well for surface cooking.

An object of the invention is to provide a deep well cooker structure of novel arrangement and to provide also a new method of combining the parts of the structure into an integrated whole. Another object is to provide a deep well casing or pot of unique construction and in which a heater or burner element is slidably mounted for movement to elevated and lowered positions. Still another object is to provide a method of fabrication permitting the employment of thin heat-reflective metal, such as for example, stainless steel etc., while providing effective means for reinforcing the thin metal to form a structurally sturdy pot or casing. Another object is to provide a process by which a plurality of casing segments or sections may be rapidly integrated to form a complete casing through the use of channel members which are interlocked with the sections both against lateral movement and longitudinal movement, and which permit ready assembly by welding, etc. Other specific objects and advantages will appear as the specification proceeds.

The invention is illustrated, in a single embodiment, by the accompanying drawings, in which—

Fig. 1 is a top plan view of a deep well cooker structure embodying my invention; Fig. 2, a perspective view showing the cylinder sections and connecting channel members or guide members in separated position and prior to assembly; Fig. 3, an enlarged broken detail sectional view, the section being taken as indicated at line 3—3 of Fig. 1; Fig. 4, a broken side view in elevation; Fig. 5, a transverse sectional view, the section being taken as indicated at line 5—5 of Fig. 4; Fig. 6, a perspective view of a modified form of structure embodying my invention; and Fig. 7, a sectional view, the section being taken as indicated at line 7 of Fig. 6.

It is desired that the walls of the deep well cooker be reflective of heat. Stainless steel is admirably suited for this purpose, the casing sheets being of very thin cross-section. The heat radiated from the burner element is reflected inwardly by the walls of the well or cylinder casing and such heat is thus confined for use in the area below the cooking vessel. The thin reflective metal, if pierced to create apertures

2

for guide members for the burner, is weakened along such lines and it is extremely difficult to form accurate channels without distorting the cylindrical structure.

I have discovered that an undistorted and true cylindrical casing body can be produced while utilizing extremely thin metal if the cylinder is formed in a plurality of sections cut to predetermined shapes and if flanged channel members are employed at spaced intervals for uniting the sections. The locking and bracing effect of the channel members is enhanced by having the channels turned laterally at their top portions so that they may be anchored within recesses provided for them in the pre-cut sections. By bringing the sections together with the channel members therebetween in interlocking position, final fabrication by welding, etc. is rendered easy and accurate. The channel members preferably terminate short of the top and the bottom of the cylindrical casing and I utilize rings at the top and the bottom for securing the ends while at the same time providing a flange for suspending the well from the top of the range.

25 In the illustration given, 10 designates a section of a cylindrical casing. I prefer to form the sections of substantially the same size and shape to facilitate manufacture but it will be understood that they may be formed of different shapes and they may be brought together in any desired number for the forming of a completed cylinder. In the specific illustration given, I provide 3 sections 10 for the forming of a complete cylinder. In the illustration given, the section 10 is provided at one side with a relatively straight edge 11 and at the top is provided with an outwardly turned portion 12, as shown more clearly in Fig. 2. The other side of the section 10 is also provided with a relatively straight edge 13 which, near the top of the section, is curved inwardly, as indicated at 14, terminating in a semi-circular recess 15. Above the recess 15, the wall is substantially straight as indicated at 16. One of the sections 10 may be punched to provide a hole 17 through which the electric cable 18 may be passed.

Between each of the sections, as shown best in Fig. 2, is a channel or guide member 19. The member 19 is U-shaped and has its inner ends turned laterally to provide flanges 20 adapted to lie against the inner walls of the sections 10. At its upper end, the channel member 19 is turned laterally along a curved portion 21 and terminates in a rounded socket 22 adapted to be snugly received within the semi-circular opening 15 of the adjacent section 10.

The guide member or channel member 19, as shown more clearly in Figs. 2 and 4, terminates a spaced distance below the top of the united sections and a short distance above the bottom of the united sections.

The sections 10 may be formed in a variety of ways. They may be cut from flat strips of metal and then formed to arcuate shape illustrated in Fig. 2 or they may be preliminarily formed in the arcuate shape and cut to the desired pattern while in such form.

The sections 10 may be united with the guide members or channel members 19 by bringing the sections together with the flanges 20 of the channel members lying against the inner walls of the sections 10. The parts are then united by spot welding 23 at spaced points, as indicated. It will be understood that the parts may be united by any other suitable means. The resulting integrated cylinder structure is extremely sturdy even though the walls are formed of thin metal because the channel members 19 provide vertical reinforcing posts or ribs while at the same time the laterally extending top portion of the channels provide a stiffening of the cylinder body along a circumferential area. At the same time, the interlocking of the laterally extending top part of the channel aids in the assembly of the operation by a preliminary locking together of the parts while also suspending the channel upon each section and positioning it accurately with respect to the adjacent section. The channel is thus anchored not only by the welding but also by engagement with the section edges both in the lateral planes and in the vertical plane.

After the cylinder has been constructed as described, I prefer to attach to the top of the cylinder a ring 26 equipped with a laterally extending suspension flange 25. The flange 25 is useful in supporting the cylinder upon the range top. A second ring 26 is drawn around the bottom portion of the cylinder and may be united thereto by screws 27, as shown more clearly in Fig. 5. Integrally formed with the ring 26 is a bottom wall 28 which may be provided with a central aperture 29. If desired, the bottom wall or flange may be provided with a concentric ring of small apertures 30, as shown more clearly in Fig. 5.

Prior to the securing of the ring 26 about the bottom of the cylinder, I prefer to introduce the heating element and the support structure 31 therefor into the interior of the casing. The support structure 31 in the illustration given, is provided with a sleeve portion 32 having 3 laterally extending guide studs 33. The studs may be provided with reduced portions extending through apertures 34 in the sleeve and secured thereto by peening over the inner portion of the lug to form the head 35, as shown more clearly in Fig. 3. The support structure 31 is provided with spider arms 36 which extend inwardly and are secured within a cylindrical center member 37. Upon this frame work are supported the electric resistance heating elements 38. The electric cable 18 which extends through the hole 17 at the bottom of the casing extends upwardly and is connected to a bracket 39 secured to the frame. From the bracket, individual electric cords lead to contacts for the electric resistance elements, as in the conventional electric burner structure.

Just prior to the attachment of the ring 26 to the cylindrical casing, I prefer to introduce the burner structure through the bottom portion of the cylinder, bringing the guide studs 33 into

5 alignment with the channel or guide members 19. The guide members 19 thus provide tracks for the guide studs 33. The ring 26 is then secured in position and the wall 28 provides an apertured closure for the deep well pot.

10 In operation, the burner structure may be raised to an upper position, the guide members 19 serving to direct the guide studs 33 laterally as they approach the top of the guide members and until the studs fall into the socket or seat 22. The movement laterally into the seat is automatic, it being necessary only for the operator to lift the burner upwardly by means of a handle or by grasping the burner directly. Upon release 15 of the burner element, the lugs 33 fall into the seats 22 and are there securely held against downward movement. By preforming the channel members in a die, a very smooth surface is provided so that the guide studs of the burner readily slide along the inner surfaces of these guides.

20 The supporting structure 31 for the burner element preferably is provided with an inner sleeve wall 40 and between the sleeves extends a flat ring portion 41 forming a companion ring with the laterally extending flange 25. The carrier or support structure 31 may be formed of any suitable material and in any desired shape.

25 When the burner is to be used in a deep well position, it may be lifted slightly and rotated to bring the guide lugs 33 into alignment with the vertical track of the guide member and the burner may then be lowered to a position in which the guide studs 33 rest upon the edge of the lower ring 26.

30 In the structure shown in Figs. 6 and 7, the upper ring 24a is united with the lower ring 26a by channel members 19a and the sections 10 are omitted. I prefer to extend the upper flange 42 of each channel member 19a so as to enclose the ring portion 24a, as shown more clearly in Fig. 7. I prefer to cut away the channel portion of the member 19a at 43 so that it rests upon the top of ring 26, as shown best in Fig. 4, the flange 45 portions 20a extending inwardly along the inner walls of the ring 26a. The parts are united by spot welding, as indicated, or by any other suitable means.

35 While in the foregoing description I have referred to stainless steel as illustrative of reflective metals which may be used, it will be understood that other reflective metals of different compositions and alloys of metals may be used for the purposes described. Further, different parts of the structure may be formed of different metals or alloys.

40 While in the forgoing specification, I have set forth a specific structure in great detail as illustrative of the invention, it will be understood 60 that such details of structure may be varied widely by those skilled in the art without departing from the spirit of my invention.

I claim:

45 1. A cylinder casing adapted for use with a deep well cooker, comprising a plurality of arcuate sections of relatively thin corrosive-resistant steel, U-shaped members between said sections and having on their inner sides laterally extending flanges abutting the inner walls of the sections and overlapping the joints of the sections, said U-shaped members being turned laterally at their upper ends to form seats, said sections having recesses therein adapted to receive said laterally turned U-shaped members, and means 50 securing said flanges to said sections.

2. A cylinder casing adapted for use with a deep well cooker, comprising a plurality of substantially equal arcuate sections of relatively thin corrosive-resistant metal equipped at their upper portions with recesses, U-shaped members between said sections and having on their inner sides laterally extending flanges abutting the inner walls of the sections to be joined, said U-shaped members being turned laterally at their upper ends along a curved line to form seats and being received within said recesses of the sections, and means securing said flanges to said sections.

3. In a deep well cooker, a cylinder comprising a plurality of arcuate sections of relatively thin corrosive-resistant steel, U-shaped members extending vertically between the sections and having on their inner sides laterally extending flanges overlapping the sections, said U-shaped members terminating short of the top of the sections, and a ring secured to the top portions of said sections and having an outwardly extending flange for supporting the cylinder on a range top, and means connecting said flanges and the sections to form a cylinder.

4. In a deep well cooker, a cylinder comprising a plurality of arcuate sections of relatively thin corrosive-resistant metal, U-shaped members extending between the sections and having on their inner sides flanges extending laterally and overlapping the sections, means connecting said flanges and sections, said U-shaped members terminating short of the bottom, and a ring encircling the bottom portion of the section and having a flange extending inwardly to provide a bottom for the cylinder.

5. In a deep well cooker, a cylinder comprising a plurality of arcuate sections of relatively thin corrosive-resistant metal, U-shaped members extending vertically between the sections and having on their inner sides laterally extending flanges overlapping said sections, means connecting said flanges and sections, said U-shaped members terminating short of the tops and bottoms of said sections, and rings secured to the top and bottom portions of the sections, said bottom ring having an inwardly extending apertured flange providing a bottom for the cylinder.

6. In a deep well cooker, a cylinder comprising a plurality of arcuate sections of relatively thin corrosive-resistant steel, U-shaped members extending vertically between the sections and having on their inner sides laterally extending flanges overlapping the sections, means connecting said flanges and sections, a burner-equipped carrier with guide studs received within the U-shaped members, said U-shaped members being turned laterally at their upper portions to provide seats for supporting the guide studs in elevated position.

7. In a deep well cooker, a cylinder comprising a plurality of relatively thin stainless steel sections, said sections having laterally extending recesses therein, U-shaped members extending vertically between the sections and having laterally turned portions adapted to be received within the recesses of said sections and having laterally turned flanges overlapping the sections, means connecting the flanges and sections to form a complete cylinder, a ring secured to the top of the cylinder and having a flange for suspending the cylinder upon a range top, a second ring encircling the lower portion of the cylinder and having an inwardly turned flange providing a bottom wall for the cylinder, and a burner-equipped carrier equipped with guide studs engaging the U-shaped members, said guide studs when moved into the laterally extending portions of said U-shaped members being supported thereby against downward movement.

EDWIN A. RUTENBER.
